Inventor:

Otto Jackmann

UNITED STATES PATENT OFFICE

OTTO JACKMANN, OF SANGERHAUSEN, GERMANY

SOAP BOX

Application filed March 18, 1926, Serial No. 95,793, and in Germany April 2, 1924.

My invention relates to improvements in soap-boxes; and the objects of my improvement are, first, to preserve the soap within the box when travelling; and second to prevent the loss of soap when putting it back into the box in moist condition after using it.

I attain these objects by the mechanism illustrated in the accompanying drawing, in which—

10 Figure 1 is a longitudinal section on the line 1—1, Fig. 3; Figure 2 is a side view of a piece of soap to be placed into the box. Figure 3, a top view of the box with a cake of soap in place, and Figure 4, a detailed view of the 15 casing containing the circle of teeth.

Similar letters refer to similar parts throughout the several views.

At the bottom part of a box *a*, preferably made of celluloid, a casing *e* is foreseen, provided with a circle of springy teeth *f*. The soap being supplied with a holder *b*, fitting into the casing *e* and adapted to be sunk into the body of the soap; a projecting knob *d* secured to said holder when pressed into the 25 casing *e* becomes engaged by a circle of teeth *f* which encircling the neck *g* of said holder takes hold of the knob, keeping the soap off the walls of the box.—

I claim:

20 A soap-box, comprising a casing, a holder fitting into said casing, said holder being adapted to be sunk into the body of the soap, a projecting knob secured to said holder and a circle of teeth secured within the box and 25 engaging said knob, substantially as set forth.

In testimony whereof I have affixed my signature.

OTTO JACKMANN.
